(57) **CLAIM**

The ornamental design for a cap for bottle for beauty care products, as shown and described.

DESCRIPTION

FIG. 1 is a perspective view of a first embodiment of a cap for bottle for beauty care products, embodying our new design;

FIG. 2 is a front view thereof;

FIG. 3 is a left-side view thereof;

FIG. 4 is a back view thereof;

FIG. 5 is a right-side view thereof;

FIG. 6 is a top view thereof;

FIG. 7 is a bottom view thereof;

FIG. 8 is a perspective view of a second embodiment of a cap for bottle for beauty care products, embodying our new design;

FIG. 9 is a front view thereof;

FIG. 10 is a left-side view thereof;

FIG. 11 is a back view thereof;

FIG. 12 is a right-side view thereof;

FIG. 13 is a top view thereof;

FIG. 14 is a bottom view thereof;

FIG. 15 is a perspective view of a third embodiment of a cap for bottle for beauty care products, embodying our new design;

FIG. 16 is a front view thereof;

FIG. 17 is a left-side view thereof;

FIG. 18 is a back view thereof;

FIG. 19 is a right-side view thereof;

FIG. 20 is a top view thereof;

FIG. 21 is a bottom view thereof;

FIG. 22 is a perspective view of a fourth embodiment of a cap for bottle for beauty care products, embodying our new design;

FIG. 23 is a front view thereof;

FIG. 24 is a left-side view thereof;

FIG. 25 is a back view thereof;

FIG. 26 is a right-side view thereof;

(Continued)

FIG. 27 is a top view thereof;
 FIG. 28 is a bottom view thereof;
 FIG. 29 is a perspective view of a fifth embodiment of a cap for bottle for beauty care products, embodying our new design;
 FIG. 30 is a front view thereof;
 FIG. 31 is a left-side view thereof;
 FIG. 32 is a back view thereof;
 FIG. 33 is a right-side view thereof;
 FIG. 34 is a top view thereof;
 FIG. 35 is a bottom view thereof;
 FIG. 36 is a perspective view of a sixth embodiment of a cap for bottle for beauty care products, embodying our new design;
 FIG. 37 is a front view thereof;
 FIG. 38 is a left-side view thereof;
 FIG. 39 is a back view thereof;
 FIG. 40 is a right-side view thereof;
 FIG. 41 is a top view thereof;
 FIG. 42 is a bottom view thereof;
 FIG. 43 is a perspective view of a seventh embodiment of a cap for bottle for beauty care products, embodying our new design, shown in a position of use with an exemplary bottle;
 FIG. 44 is a front view thereof;
 FIG. 45 is a left-side view thereof;
 FIG. 46 is a back view thereof;
 FIG. 47 is a right-side view thereof;
 FIG. 48 is a top view thereof; and,
 FIG. 49 is a bottom view thereof.
 The broken lines are shown for the purpose of illustrating both parts of the article as well as environmental subject matter of an exemplary bottle and form no part of the claimed design.

1 Claim, 8 Drawing Sheets
